UNITED STATES PATENT OFFICE.

JOHN G. BOWMAN, OF KANSAS CITY, MISSOURI, ASSIGNOR OF ONE-HALF TO WILLIAM C. HASELTINE, OF KANSAS CITY, MISSOURI.

VALVED SPARK PLUG.

Application filed July 25, 1927. Serial No. 208,205.

The invention relates to valved sparkplugs, and particularly to sparkplugs constructed with ventilating valves—that is, with means for admitting air through the sparkplugs.

5 It is an important aim of the invention to provide a novel coordination of the valve and the cylinder of an internal combustion motor to the end of effecting efficient functioning of the valve device for admission of 10 air through the plug, and to prevent escape of gases, at the same time that the appliance operates quietly with a minimum of wear.

It is a further aim to enable the embodiment of the valve for such plug in an extremely inexpensive form.

Additional objects, advantages, and features of invention reside in the construction, arrangement and combination of parts as will be understood from the following description and accompanying drawings, wherein

Figure 1 is a central vertical sectional view of a plug constructed in accordance with my invention.

25 Figure 2 is an enlarged central longitudinal sectional view of the valve, alone.

Figure 3 is an elevational view of the valve case.

30 Figure 4 is a view similar to Figure 2 of another embodiment of the invention.

There is illustrated a plug 10 engaged in the head of a cylinder 11 of an internal combustion engine, the plug being of a conventional construction including the case 10, a porcelain core electrode 13 and retaining gland 14 for the electrode. A horizontal interiorly threaded opening 15 is formed through the case 10 inwardly of the shoulder of the porcelain, and screwed into the opening 15 there is a thimble-like cylindrical valve casing 16, adapted to be drawn from sheet metal. This is exteriorly threaded at its open end and screwed snugly into the passage 15. Intermediately of the length of the case 16 a port 17 is formed, while the inner end edge of the case is curved inwardly as at 22'. Loosely slidably in the case 16 there is a valve 19 similar to the case having its outer end integrally closed by a head, while its inner end is open. One or more ports are formed in the side of this valve or a series of ports, and alined with these a circumscribing groove 21 is formed, which

may be produced by indenting the periphery of the valve by spinning or otherwise after 55 having first been drawn to the cylindrical thimble shape. It is to be noted that the valve 19 has a head or closed end 22 snugly and slidably fitted in the case 16. The port 17 being spaced a substantial distance from 60 the outer closed end 18 of the case 16, it will be seen that a certain dash-pot action will occur in the movement of the valve head 22 in that part of the case outwardly of the port 17. The distance between the 65 inturned end portion 22' of the case 16 and the port 17 is the same as the distance between the inner or open end of the valve 19 and groove 21, so that when the end of the valve rests against the inturned portion 22' 70 the groove 21 is alined with the port 17.

In the manufacture of this device, the case is formed as a simple headed cylinder without the inturned portion 22' and the valve formed completely, so that it is 75 adapted to function suitably in the case. The valve is then introduced in the case and the edge of the case turned in at 22' so that when the valve rests against the inturned portion, the groove 21 will aline 80 with the port 17. The threads upon the case may be formed at any convenient stage in the manufacture, and after assembly of the parts as indicated, may be screwed into the passage 15 of the plug until its inner end 85 lies at, or adjacent, the inner face of the plug-case, but stopping short of the porcelain core.

In use, when a motor equipped with this plug is on compression stroke, it will be 90 seen that the valve will be forced outwardly into the case 16, and will so remain during the working stroke and the scavenging stroke. On the suction or intake stroke of the engine, however, it will be apparent 95 that the valve will be drawn inwardly so that the groove 20 alines with the port 17, admitting air around the interior of the plug, which will clear the plug of partially consumed gases and carbon, and tend also 100 to facilitate the burning off of carbon from parts of the plug, which may become coated therewith.

It is important to note, however, that an additional function is attained in this valve 105 by reason of the nature of the construction

shown, which is of material advantage in such devices where quietness of operation is desired. A substantial space or dash-pot 23 is formed in the outer part of the case 5 beyond the port 17, and on the compression stroke, the tendency of the valve to be moved abruptly to the outer limit of its movement is checked by dash-pot action in the portion 23. Similarly, at the beginning of the intake stroke of the motor a slightly vacuous condition produced in the dash-pot after a certain amount of movement of the valve toward open position will prevent it from moving so rapidly to the inner limit of its 10 movement as to produce any objectionable click, and this will also minimize wear upon the inturned part of the case and the end of the valve.

Any gas which may remain under pressure 20 in the outer end of the case on completion of the working stroke will gradually move the valve toward open position on the scavenging stroke or at the completion thereof.

It is possible to construct my valve without the use of dash-pot action but with a cushion for the valve of mechanical construction, as shown in Figure 4, where in place of the dash-pot chamber 23 a packing 25 is introduced in the closed end of the casting, and a suitable vent 25 provided to permit free action of the valve until checked by the cushion. Under opposite movement of the valve—that is, to open position— 30 necessity for cushioning is less, and sound is minimized by reason of the rapid movement of air inwardly through the port of

the valve, which is at a rate in excess of the rate of propagation of sound waves.

I claim:

1. In a structure of the character set forth, a cylindrical valve case having a closed end, an open end and a lateral port spaced from said closed end, a valve of similar form snugly slidable in the case having its closed end next the closed end of the case, means to limit movement of the valve toward the open end of the case, said valve having a lateral port constructed and arranged to communicate with the port of the case when adjacent the outer limit of its movement in the case.

2. In a valve of the character described, a tubular casing having a closed head at one end, a valve of like form slidable in the case with its head next the head of the case, said valve having a port in the side spaced from its head, said case having a port in its side differently spaced from its head and adapted to register with the port of the valve when the valve is at one limit of its movement.

3. In a valve of the character described, a case of tubular form having a closed end and an open end, a lateral port intermediate of the length of the casing, a cushion material within the case at the closed end, a valve of similar form snugly slidable in the case with its closed end toward the cushion and having a lateral port adapted to align with the port of the case at one extreme limit of movement of the valve.

In testimony whereof I affix my signature.
JOHN G. BOWMAN.
